UNITED STATES PATENT OFFICE.

OSCAR G. EDMOND, OF SPOKANE, WASHINGTON, ASSIGNOR OF ONE-HALF TO WHITE
PINE SASH COMPANY, OF SPOKANE, WASHINGTON.

MORTISING MACHINE.

Application filed July 25, 1924. Serial No. 728,247.

The present invention relates to improvements in mortising machines for use in the art of wood working and especially adapted for the purpose of forming, by punching, sockets or mortises in the opposite sides of an inner or intermediate bar of a window sash.

While the machine of my invention is applicable for other uses, for convenience of illustration and description I have exemplified its use in connection with the manufacture of window sash and particularly for mortising the inner or intermediate bars of the sash which support the panes of glass. The machine is designed to simultaneously punch a socket or mortise in the wood bar, at both sides thereof, these mortises or sockets being adapted to receive the tenons of cross intermediate bars when the window sash is subsequently assembled.

By the utilization of my invention, provision is made for a machine which is comparatively simple in construction and operation, inexpensive in cost of manufacture, rapid in the performance of its functions, reliable, and efficient.

The invention consists in certain novel combinations and arrangements of parts involving a pair of opposed reciprocating punching dies and their operating mechanism together with feed and stop mechanism for the wooden bar, and other features as will hereinafter be more fully set forth and claimed.

In the accompanying drawings I have illustrated one complete example of the physical embodiment of my invention wherein the parts are combined and arranged in accordance with the best mode I have thus far devised for the practical application of the principles of my invention.

Figure 1 is a view in elevation at the operator's side of a machine embodying my invention.

Figure 2 is an enlarged detail view, from the inner side of the machine showing the actuating mechanism for the reciprocating dies and the feed-stop device.

Figure 2^a is a transverse sectional view through the wheel and disk of Fig. 2 for actuating the die mechanism and stop-feed mechanism.

Figure 3 is a vertical, transverse sectional view of the machine looking outwardly at line 3—3 of Figure 1 or line 3—3 of Fig. 5. 55

Figure 4 is a view in elevation at the rear or delivery end of the machine, as seen from the left in Figure 1.

Figure 5 is a top plan view of the machine. 60

Figure 6 is an enlarged, vertical, transverse sectional view at line 6—6 showing the feed chains and adjusting means therefor.

Figure 7 is an enlarged detail transverse sectional view at line 7—7 of Fig. 1 showing the reciprocating dies. 65

Figure 8 is a perspective view of one of the dies.

The wooden sash bar is shown in cross section at A in Figure 7 between the reciprocating dies, and the two mortises B and C at opposite sides of the bar are also indicated in this view. It will be understood that other objects or articles may be punched, and the machine may be adapted or adjusted to various sizes of these bars or objects. 70 75

In the preferred form of the invention the machine is preferably made portable and self-contained, and its frame 1 which is supported on wheels 2, carries an electric motor 3 for actuating the several devices forming the machine. A drive shaft 4 is journaled in bearings 5 near the bottom of the machine frame and is operated from the motor shaft 6 by the pulley 7, belt 8, and the large pulley 9 which latter pulley is carried by the drive shaft. 80 85

A power shaft 10 which extends longitudinally of the machine is journaled in bearings 5 parallel with and above the drive shaft and is driven from the latter by drive pinion 11 and driven gear 12 which gear is loose on the power shaft and forms part of a clutch device for co-action with a tight clutch member 13 on the shaft. By means of the clutch lever 14 and connecting link 15, the machine may be started, stopped and controlled by the operator. 90 95 100

The wood bar A to be mortised by punching is mechanically conveyed across the machine top or table 16 from right to left in Fig. 5, and is entered or introduced to the machine on the guide extension 17 under the

flat spring arm 18, at the right of the machine. The spring arm is bolted to a longitudinally adjustable block 19 and the slideable block is fixed in position on the guide flange 20 of a transversely adjustable carried block 21 which latter is slideable in the groove 22 in the top 16.

The wood bar is pushed by hand under the spring arm 18 in between a pair of endless conveyer chains 23 and 24 horizontally disposed above the top of the machine and adjustable laterally thereof. These chains travel in opposite directions with their parallel inner and adjoining flights spaced apart and moving in the same direction to frictionally grip the wood bar A with a resilient clamping action for the purpose of advancing the wood bar while it is free to be advanced. While the bar is positively held stationary these chains will continue to move along the sides of the wood bar until after the punching operation, when the bar is freed to advance, and then the chains again become operative to advance the wood bar.

The conveyer chains are supported and operated by two pairs of pulleys 25 25' and 26 26' fixed to rotate with the respective vertically disposed shafts 27 27' and 28 28'.

30 The upper ends of all of the shafts are journaled in top bearing plates 29 which plates form the tops of chain frames or boxes 30 and 30' that support and guide the movements of the chains, above the table 16.

35 The chains are driven by their shafts 27 and 28 and sprocket wheels 25 and 26, the shafts as shown in Fig. 3 extending down through the table top and within the interior of the machine frame and provided with bearing brackets 22' attached to the frame 1. A worm shaft 31 which extends transversely of the machine and is journaled in bearings 32 in the frame 1 is provided with a worm 33 that engages the worm wheel 34 on the power shaft 10, and gear couples 35, 35 between the worm shaft and the two shafts 27 28 transmit power to the latter for operating the chains.

50 The conveyer chains exert a resilient pressure against the opposite sides of the wood bar A in gripping it and for this purpose chains and chain frames are capable of a slight pivotal movement on their shafts 27 and 28 as a center of movement. At a suitable location from the shafts 27 and 28 each chain frame is provided with a depending lug 36 which passes down through a slot 36' in the top 16. In these threaded lugs are alined bolts 37 having a bearing in the respective brackets 38 depending from the opposite side edges of the table top, and each provided with a hand wheel 39 at its outer end. Between the bearing lug 38 and adjusting nuts 40 on the bolts a coiled spring 41 is interposed. By turning the hand

wheels the chains and their frames may be swung on their pivotal centers 27 and 28 to vary the relative positions of the chains. By this means the resilient pressure of the two chains against the opposite sides of the wood bar is regulated to insure proper action of the chains in advancing the wood bar and to permit the movement of the chains while the wood bar is being held stationary for punching.

75 As the wood bar A is conveyed by the gripping chains along the longitudinal center of the machine top or table it passes across the top and partly over an extension 42 of the machine until it encounters a stop 80 or detent 43 that is vertically reciprocable through a slot in the extension and which will hereinafter be described.

85 A spring arm 44 disposed in line with the spring arm 18 at the longitudinal center of the machine bears upon the top surface of the wood bar to hold it in place on the table. This arm is adjustably held in a bridge bar 45 disposed transversely of the machine and above its top, and the bridge bar has 90 end collars 46 vertically adjustable on a pair of supporting pins 47 fixed to the table at opposite sides thereof.

95 When the movement of the wood bar is halted by the stop 43 and the bar remains stationary for a period of time, the two mortises B and C are punched in the opposite sides of the wood bar by a pair of dies 48 and 49, which act simultaneously.

100 These oppositely acting dies or punches are each reciprocable through a head as 50 and 51, and as shown in Figure 8 each die has a shank 52 seated in a punch bar 53 that is screw threaded and provided with a nut 54 and collar 54'. The collars 54' 105 are slidably supported in perforated lugs 55, and a coiled spring 56 on each punch bar is interposed between the nuts 54 and heads 50 51, to hold the dies normally in retracted position and to withdraw them 110 from closed position after the working stroke of the dies.

115 The heads 50 51 and lugs 55 are rigid with their base plates 57, 58 (Fig. 7) and these plates are slidably adjustable in the grooved, horizontal, transverse guide plate 59. These base plates also have vertically disposed plates or flanges 57' and 58' that are guided in the grooved plate 59'. For longitudinally moving the dies and their 120 carriages in order to adjust the carriages and dies at opposite sides of the longitudinal center of the machine and at opposite sides of the wood bar I utilize a wheel 60 and a right-and-left screw-bar 61 threaded 125 in lugs 62 of the respective flanges 57' and 58' as best seen in Fig. 4.

130 The dies are adjustable in their heads 50 51, by turning the nuts 54 on the punch bars 53, toward or away from the longitudinal

center of the machine to decrease or increase the punching movement of the dies 48. The supports 57 and 58 for the dies are also adjustable transversely of the machine by 5 turning the hand wheel 60.

The two dies are simultaneously pushed inwardly to punch a mortise in the wood bar by means of push bars 63 and 64 which project upwardly through slots 65 of the plates 10 57 and 58 and their ends are adapted to engage the outer ends of the push bars.

The push bars are each pivoted at 66 to one of the flanges 57' 58' and near their lower ends these bars are joined by a spring 15 67 which normally holds their upper free ends out against a stop bolt 68 in a threaded lug 69 at each side of the machine and located at the outer ends of the plates 57 and 58.

20 At their lower ends these vertically disposed push bars are joined by pivoted links 70 and 71 disposed at an angle to their bars and pivotally joined together and carrying at their joint a roller 72. The pivoted push bars and their links thus form a toggle frame which when actuated will serve to push inwardly the two dies and their punch bars.

The toggle frame is actuated from a 30 flanged wheel 73 carried on the end of the power shaft 10 and equipped with a laterally projecting roller and pin at 74. The link 70 is located in the path of movement of this roller as it revolves with the flanged wheel and the roller contacts at the lower edge of the link and rides thereon as it lifts the link. The lifting of the link tends to spread the toggle frame and swing inwardly the upper free ends of the push bars to 35 make the working stroke of the reciprocating dies. After the roller 74 passes its highest point of travel, it descends and permits the springs 56 and 67 to retract the dies and 40 flex the toggle frame back to inoperative or closed position.

The toggle frame is guided in its movement by means of a vertical, grooved guide plate 75, attached to the machine frame and forming a vertical guide way for the roller 50 72.

55 After the dies have punched the mortises and have been withdrawn therefrom the stop or detent 43 is withdrawn from its normal elevated position for passage of the punched or mortised wood bar A as it is advanced by the conveyer chains. The bar is thus pushed along the way between the guide rails 76 and 77 of the extension 42, as best seen in Figure 5.

60 The stop 43, which is normally held in elevated position by a spring 43' as shown in Fig. 4, is withdrawn or lowered for passage of the wood bar is actuated by a double rock-arm 78 on the rock shaft 78' journaled 65 at the underside of the extension 42 and

disposed longitudinally of the machine at one side of its center, and to which arm the spring 43' is connected. A connecting rod 79 is pivoted on one end of this rock arm and at its lower end the rod is connected to a lift 70 lever 80, which latter lever is pivoted at 81 as seen in Fig. 4. The free end of the lift lever is elevated by contact therewith of a laterally projecting pin 82 carried by a disk 83 keyed to the shaft 10 and located 75 within the flanged or cupped wheel 73. The periphery of this disk within the wheel 73 is cut away through approximately one-half its circumference to form an arcuate slot 84 within the flanged wheel, and a pin 85 carried at the inner side of the flanged wheel is located in this slot. As seen in Fig. 2^a the flanged wheel 72 is secured on the end of the power shaft 10 by a central screw or bolt 86. By this arrangement of the disk 85 and wheel the latter may be turned to secure the proper relative distance between the pin 82 of the detent operating device and pin 74 of the die operating mechanism, and after the screw 86 has been tightened the disk 90 and wheel will co-operate at predetermined periods for punching the wood bar and withdrawing its detent.

The supporting attachment for the reciprocating dies at the end of the machine 95 frame and which attachment carries the toggle frame, may be vertically adjusted by means of the hand wheel 87 and screw bar 88, which bar is supported in the threaded horizontal lug 89 on the machine frame as seen in Fig. 4. A threaded yoke 90 integral with and projected from the plate 59' receives the screw bar, and by turning said bar the die attachment may be moved relatively 100 (and in a vertical plane) to the machine 105 frame 1.

The wood bars are fed from right to left in Figure 5 longitudinally of the machine, the conveyer chains gripping one bar to push the preceding bar against the stop 43 and in 110 this position the first bar is retained while the dies reciprocate. Then the detent or stop 43 is withdrawn and the continuously moving chains become effective to again push the wood bar through the machine to discharge 115 the mortised bar and present the following bar to the detent 43, which returns to operative position after being withdrawn for passage of a completed bar. The feed chains are adapted to assert a resilient pressure 120 against the sides of the bars and the width of the bars may vary within limits and yet be held by the chains with sufficient friction to feed the bars. The dies may be adjusted to punch bars of varying widths, and the 125 dies may be adjusted to vary the length of their working strokes, to increase or diminish the depth of the mortise. The die supporting mechanism may be adjusted vertically to raise or lower the dies with relation 130

to the wood bar for punching, and of course various forms or shapes of dies 48 may be used.

Having thus fully described my invention, 5 what I claim as new and desire to secure by Letters Patent is—

1. The combination in a mortising machine of a work-feed mechanism comprising a table and spaced resilient means for holding the work to the table, a pair of endless, 10 constantly moving feed chains, a detent in the path of movement of the work, means for exerting a resilient pressure of said chains at opposite sides of the work, and means for retracting the detent after the mortising operation to permit passage of the work.

2. The combination with a pair of spaced, endless, constantly moving feed chains and means for exerting a resilient pressure of 20 said chains at opposite sides of the work, a detent normally in the path of movement of the work and means for retracting said detent for the passage of the work and for restoring said detent after the passage of the 25 work.

3. The combination with a pair of spaced endless chains, supporting shafts and wheels therefor, of a supporting frame for a pair of shafts at one end of the chains, means for 30 driving the shafts at the other ends of the chains, and means co-acting with said frames for exerting a resilient pressure on work between said chains.

4. The combination with a pair of spaced 35 endless chains, a pair of supporting shafts and pulleys for each chain and a frame for each chain and its shafts, means for driving the shafts at one end of the chains, means for laterally adjusting the frames and 40 chains, and means co-acting with the adjusting means for exerting a resilient pressure on work between the chains.

5. The combination with a pair of spaced 45 endless chains and frames therefor, a pair of pulleys in each frame for supporting the chains and shafts for said pulleys, of means for operating the shafts at one end of the chains, a screw device connected to each frame for lateral adjustment thereof, and a 50 spring co-acting with each screw device for exerting a resilient pressure on work between said chains.

6. The combination with a pair of adjustable cross plates each having a head and 55 spaced lug, of a nut slidable in each lug and provided with a collar, a punch bar threaded in each nut and a die in each bar reciprocable in a head, a retracting spring interposed between each collar and lug, and means for 60 actuating said bars for an operating stroke of the dies.

7. In a mortising machine the combination with a pair of opposed reciprocable dies of operating mechanism therefor comprising a pair of spaced pivoted push bars and pivoted angularly disposed links connected to said bars forming a toggle frame, and a rotary member carrying a contact device for intermittent co-action with said frame. 65

8. In a mortising machine the combination with a pair of reciprocable dies and a toggle frame operatively connected therewith for actuating the dies, of a guide roller on said frame and a guide plate therefor, and a rotary disk having a laterally projecting 70 contact member thereon for co-action with a portion of the frame. 75

9. In a mortising machine the combination with a pair of reciprocable dies of operating mechanism therefor comprising a pair of spaced pivoted push bars and a spring connecting said bars, a pair of pivoted angularly disposed links pivoted at the ends of said bars and a guide roller at the pivotal connection between said links, a fixed guide 80 plate for said roller, a rotary wheel, and a contact pin on said wheel adapted to coact with an edge of one of said links. 85

10. In a mortising machine the combination with a feed mechanism, a mortising device and a stop device, a power shaft and transmission supports between said shaft and feed mechanism, a driving member carried by the shaft and operative connections therefrom to said mortising device, a driving 90 member on the shaft and operating connections therefrom to the stop device, and means for relatively adjusting said driving members relatively to said shaft. 95

11. The combination in a mortising machine with a feed mechanism, a mortising device and a stop device of a power shaft and transmission supports therefrom to the feed mechanism, a flanged wheel carried by the shaft and operative connections therefrom to the mortising device, a slotted disk within the wheel and fixed to said shaft and a pin on the wheel co-acting with said disk, operating connections between the disk and stop device, and means for relatively 100 adjusting the disk and wheel on said shaft. 105

12. The combination in a mortising machine with a detent and means for normally holding said detent in operative position, a rock shaft and connections therefrom to said detent, a rotary actuating member and a pin thereon, a pivoted lift lever in the path of movement of said pin, a crank arm on the rock shaft and a link connecting said arm and lever. 115

In testimony whereof I affix my signature.
OSCAR G. EDMOND.
